UNITED STATES PATENT OFFICE.

HENRY A. RUDD AND FRANK B. COLLINS, OF BARBERTON, OHIO, ASSIGNEES TO THE DIAMOND MATCH COMPANY, OF CHICAGO, ILLINOIS, A CORPORATION OF ILLINOIS.

JACK FOR PORTABLE HOISTS.

1,109,148.

Specification of Letters Patent.

Patented Sept. 1, 1914.

Application filed November 7, 1911. Serial No. 658,947.

To all whom it may concern:

Be it known that we, HENRY A. RUDD and FRANK B. COLLINS, citizens of the United States, and residents of Barberton, in the 5 county of Summit and State of Ohio, have invented certain new and useful Improvements in Jacks for Portable Hoists, of which the following is a specification.

The present invention relates to jacks for 10 portable hoisting apparatus and more especially to jacks for supporting the tackle blocks of lumber pilers.

The object of our invention is to provide 15 a structure which combines the merits of lightness, strength and efficiency, and which, when not in actual service, may be readily folded into small compass for convenience of packing and transportation.

Accordingly our invention comprises a 20 jack structure embodying novel features of construction which will be hereinafter described and claimed.

The invention also comprises features of 25 construction which will be hereinafter described and claimed.

In the drawings Figure 1 is a side elevation of a jack embodying an efficient form of our invention, the structure being represented as operatively mounted on a lumber 30 pile and supporting a tackle block, and the parts as partially folded or collapsed being indicated by dotted lines. Fig. 2 is a plan of the jack with the tackle block omitted, the dotted lines showing the parts as in 35 folded position.

A, B designate two frame sections so constructed and interjointed that one section can be folded upon or within the other. These sections are preferably of substantially triangular form with their basal ends jointed or pivotally connected, one of the sections, as A, constituting a supporting element for the structure and the other, as B, a derrick-like arm or "boom" for the suspension of a 45 tackle block or blocks, as C.

The members of the triangles are preferably composed of pipe bars as illustrated; the section A comprising two converging side bars 1, which are united at their apex 50 by a bolt 2, and a basal bar 3 which is conveniently fastened to the spaced ends of the side bars by a through bolt 4, and the section B comprising two converging side bars 5 which are also united at their ends by a bolt 55 6 and are pivotally supported and jointed at

their spaced ends to the section A by the connecting bolt 4.

On the apex bolts are joint members comprising pivoted angle pieces 7, 8 respectively, having inwardly extending arms which are 60 connected by a tie or tension member 9. Preferably this member 9 comprises two sections jointed together as at 10, and attached at their extremities to the respective arms by 65 links 11. The downwardly extending arms of the angle pieces 7, 8 have provisions, such as perforations, for the attachment of hooks, or the like, whereby an anchoring means, such as the chain, 12, can be secured at the apex of the section A, and a tackle block, as 70 C, can be suspended from the apex of the section B, as illustrated.

The jointed skeleton-like structure above described combines lightness and strength with simplicity of construction and operation. It may be readily erected in folded condition upon a suitable support, as, for example, a lumber pile adjoining one that is being built up, the section A being of sufficient length to project to or beyond the 75 sides of the supporting structure. A chain, or the like, is hooked into the eye of the angle piece of the section B. The latter sec- 80 to the ground or other stable body; and a tackle block is hooked into the eye of the 85 angle piece of the section B. The latter sec- 90 tion is then opened out to project the tackle block forwardly and upwardly beyond the lumber pile, and thus, similarly to a "boom", support the block in position for efficient op- 95 eration with the tackle of a lumber sling or lift.

It is to be noted that when the section B is projected as just mentioned it is held in position for efficient service by the tie-rod and chain connections, and yet, as indicated by the dotted lines, this section and the tie-rod, when the structure is free from a load, may be readily collapsed and folded into the section A for convenience of packing and trans- 100 portation.

We claim—

1. In a folding jack for portable hoists, two pivotally connected skeleton sections, whereof one constitutes a base portion and the other a tackle supporting portion, said sections being so constructed and interjointed that one may be folded upon or within the other, a tie-connection for the said sections comprising a plurality of rods 105 110

and joint members between the outer extremities of said rods and the respective sections, whereby the said rods may be opened out or folded with the said sections, anchor 5 means pivotally connected with the joint member of the base portion, and tackle means pivotally connected with the other joint member.

2. In a folding jack for portable hoists, 10 two triangular frame sections pivotally connected at their wider or basal ends, angle pieces pivotally connected to the apices of said sections, a tie-connection for the said sections comprising a plurality of rods which

are jointed together and to the said angle-pieces, a tackle-block connected with the angle-piece of one of said sections, and a depending chain connected with the angle-piece of the other section.

Signed at Barberton in the county of Summit and State of Ohio this 3rd day of November 1911.

HENRY A. RUDD.
FRANK B. COLLINS.
